corporation of Illinois

Application December 13, 1935, Serial No. 54,227

7 Claims. (Cl. 194—92)

This invention relates to coin controlled devices.

It is an object of this invention to provide an improved coin controlled device which is relatively simple and inexpensive in construction and efficient in use.

Another object of the present invention is to provide a novel device, adapted to be associated with any coin controlled vending or amusement device such, for example, as a pin and marble game, or the like.

An additional object of the present invention is to provide a novel device, adapted to be associated with the coin slide or coin control, of a coin controlled machine or apparatus, and coacting with the said coin control, to permit two successive operations of the said machine or apparatus.

A further object of the present invention is to provide, in combination with a coin slide of the type which has a limited amount of lost motion during its operative stroke, such as in the slide down and described in the Tratsch and Hall Patents Nos. 1,908,370 and 1,908,752, means for utilizing this lost motion of the slide for effecting a second operation of the operating mechanism controlled by the slide without necessitating the insertion of a second coin or token into the coin aperture of the same.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a view, partly in section, and partly in side elevation, showing a preferred form of the present invention associated with a part of the operating or control mechanism of a coin-controlled amusement apparatus;

Fig. 2 is a fragmentary side elevational view of the device shown in Fig. 1, with several of the parts in changed position;

Fig. 3 is a sectional top plan view, on line 3—3 in Fig. 1;

Fig. 4 is an elevational view, partly in section, on line 4—4 in Fig. 1; and

Fig. 5 is a schematic wiring diagram of an electrical circuit embodied in the invention.

A preferred form of the present invention is shown in the drawing, is therein generally indicated at 10, and is shown associated with a coin-controlled amusement apparatus, which is generally indicated at 11, and which includes a cabinet 12.

Slidably mounted in an end wall 13 of the cabinet 12 is a coin slide 14, which is preferably of the type shown and described in the Tratsch and Hall Patents, Nos. 1,908,370 and 1,908,752.

This slide or control member 14 is of the type, 5 as disclosed in the said patents, which has a limited amount of lost motion in its idle or locked condition (right to left, Fig. 1), that is, the slide 14 may be moved partially inwardly (right to left, Fig. 1), without inserting a coin or token 10 into the coin aperture of the same, before the fraud-prevention devices or dogs 65 become effective to prevent further inward movement of the slide but when freed, as by deposit of a coin, the slide may be completely or fully reciprocated. 15

Carried by, and depending from, the inner end portion of the coin slide 14, is an arm 15, and connected to this arm 15, as at 16, is one end portion of a link or push bar 17.

Formed in the push bar 17 is an elongated slot 18 and projecting into this slot 18 is a pin 19, this pin 19 being attached to, and carried by, a link member 20 which is pivotally mounted adjacent its upper end, as at 21, in the cabinet 12.

Pivottally connected to the member 20, adjacent 25 the lower end of the latter, as at 22, is a link 23 and formed in the lower end portion of this link 23 is an elongated slot 24. Projecting into this slot 24 is a pin 25 which is attached to, and projects laterally from an operating arm 26 of 30 an instrumentality such as the disc 27, this disc 27 forming part of a timing or control device which is generally indicated at 28, and which forms the subject matter of U. S. Patents Nos. 1,353,850, 1,773,697 and 1,795,969; it being understood that the timing device 28 forms part of 35 the operating mechanism of the machine or apparatus which is arranged in the cabinet 12.

The disc 27 is rotatably mounted, as at 29, upon a support 30, which is arranged in the cabinet 11, and formed in the peripheral edge of the disc 27 is a notch or recess 31. Engageable in this recess or notched portion 31 of the disc 27 is a pin 32 which is carried by, and projects laterally from, a member 33, this member 33 being pivotally mounted, between its ends, as at 34, upon the support 30. Carried by the member 33 is a small disc (of nonconductive material) 35 which is engageable with a contact 36 which, in turn, is engageable with a contact 37, these contacts 36 and 37 forming a switch 38 which may be employed for the purpose of controlling the operation of any electrically operated or controlled mechanism which may be arranged in the cabinet 12 of a coin-controlled amusement or 50 55

article vending device, or analogous apparatus or machine.

Pivots mounted in the cabinet 12, as at 39, is a ratchet 40 which is provided with a row or rack of teeth 41. Pivots connected at one end, as at 42, to the ratchet 40, is a link 43, this link 43 having a pin and slot connection, at 19, with the member 20.

Pivots mounted on the ratchet 40, as at 44, and carried thereby, is an actuating arm or pawl 45, this arm or pawl 45 having an end portion 47 which is engageable with a pin 48 which is carried by, and projects laterally from, the push bar 17. The pawl 45 is engageable with a laterally extending arm 46 of the ratchet 40.

Attached, as at 49, to the ratchet 40, is one end of a coil spring 50, the other end of this coil spring 50 being anchored in the cabinet 12, as at 51.

Pivots mounted in the cabinet 12, as at 52, is a latch dog 53 and this latch dog 53 has an arm 54 which is engageable with the teeth 41 of the ratchet 40. Attached to the dog 53, as at 55, is a coil spring 56 which normally urges the dog 53 (into initial position, Fig. 1).

Carried by, and projecting laterally from, the push bar 17 is a pin 57 which normally engages a contact 58 so as to urge the latter into engagement with a contact 59, these contacts 58 and 59 forming a so-called full stroke switch 60.

The switches 38 and 60 are arranged in an electrical circuit 61 (Fig. 5) which also includes a suitable source of current 62 which may be a battery of dry cells or the like arranged in the cabinet 12. Any desired mechanism may be arranged in the circuit 61 or operated thereby, and, for the purpose of illustration, the circuit 61 is shown as having a motor 63 arranged therein, this motor 63 being intended to actuate any operating mechanism or device which it may be desired to arrange in the cabinet of a coin-controlled machine or apparatus. Attached to the coin slide 14 is a resetting spring 64.

Operation

The parts are normally disposed in the position in which they are shown in Fig. 1, and when a coin or token is inserted into the coin aperture of the coin slide 14 and the latter is pushed in (right to left, Fig. 1), the push bar 17 is correspondingly moved, by reason of its connection, at 15—16, with the coin slide 14. This movement of the push bar 17 (right to left, Fig. 1) acts, through the pin and slot connection 18—19, to pivot the member 20, at 21, and the member 23, at 25, (clockwise, from dotted to full line position, Fig. 2). This movement of the member 23 is transmitted, through the pin and slot connection 24—25, to the controlled instrumentality or disc-like member 26—27, thereby pivoting the latter, at 29, (from dotted to full line position, Fig. 2), thereby moving the notched portion 31 of the disc 27 out of engagement with the pin 32, whereupon the pin 32 will ride the periphery of the disc 27. During this operation the member 33 is pivoted at 34, (counterclockwise, from the position in which it is shown in Fig. 1 into the position in which it is shown in Fig. 2), and during this movement of the member 33 the disc 35, which is carried by the member 33, engages the contact 36, thereby forcing the contact 36 into engagement with the contact 37 and thus closing the switch 38; it being understood that this closing or operating of the switch instrumentality 38 may be utilized to actuate any electrically oper-

ated or controlled mechanism which it may be desired to arrange in the cabinet 12, or in the circuit 61, such, for example, as the motor 63. It is to be noted, however, that the circuit 61 is not closed until the coin slide 14 and push bar 17 are reset into their initial position (left to right, Fig. 2, or as shown in Fig. 1) by the action of the resetting spring 64, this movement of the push bar 17 causing the pin 57 carried thereby to engage the contact 58 and urge the same into engagement with the contact 59, thereby closing the switch 60.

When the coin slide or control member 14 and slide bar 17 are moved inwardly (right to left, Fig. 1), to effect the initial actuation of the operating mechanism 63, etc. by a full stroke operation of the slide, the member 20 acts, through the link 43, to condition the repeat operating mechanism for subsequent actuation by a partial or limited movement of the control or slide 14, specifically by pivoting the ratchet 40, at 39 (clockwise, from the position in which it is shown in Fig. 1 to the position in which it is shown in Fig. 2), thereby moving the end portion 47 of the pawl 45 into the path of movement of the pin 48 which is carried by the push bar 17, and when the push bar 17 is retracted (left to right, Fig. 2) the link mechanism 43—20—23 remains as in full line position, Fig. 2, by reason of the pin and slot connection 18—19 of the push bar 17 with the link 20, and during this return movement of the push bar 17 the pin 48 carried thereby engages the end portion 47 of the pawl 45 and thereby pivots the latter, at 44 (counterclockwise, Fig. 2), thus allowing the pin 48 to pass by the end portion 47 of the pawl 45 into its initial position (as in Fig. 1). During this operation the arm 54 of the dog 53 rides over the teeth 41 of the ratchet 40 and latches the ratchet 40 in the position which it is shown in Fig. 2, and against retroactive movement, by its resetting spring 50.

After the controlled or operating mechanism or other instrumentality (motor 63, etc.) has been in operation, a predetermined length of time, the circuit 61 is opened by the action of the timing device 28, the disc 27 of which is gradually rotated (counterclockwise, from full to dotted line position, Fig. 2), thereby opening the switch 38 and the circuit 61 and again positioning the parts 20—23—26 in their initial position (as in dotted lines, Fig. 2, full lines, Fig. 1).

Accordingly after the parts 20—23 and 26 have thus been returned to their initial position, as in dotted lines, Fig. 2, after the initial operation of the coin slide 14 and associated parts, the controlled mechanism 28—38—63, and associated parts, in the cabinet 12, may again be moved into effective position, that is, the circuit 61 may again be closed, without inserting another or second coin or token into the coin aperture of the coin slide 14, and this is accomplished by taking advantage of the lost motion in the slide 14, that is, by taking advantage of the fact that the slide 14 may be moved partially inwardly (right to left, Fig. 1), (full to dotted lines, Fig. 3), without inserting a second coin or token into the coin aperture of the slide 14, before the fraud-prevention devices or dogs 65 become effective to prevent further inward movement of the slide 14 (right to left, Fig. 1).

Accordingly when the parts are positioned in dotted lines, Fig. 2, and the coin slide 14 is moved partially inwardly (right to left, Figs. 1 and 3), without inserting a second coin or token into the

coin aperture of the same, the push bar 17 is correspondingly moved and during this operation the laterally extending pin 48, which is carried by the push bar 17, engages the end portion 41 of the pawl 45 and moves the latter a corresponding short distance from the position in which it is shown in Fig. 2, thereby pivoting the ratchet 40, at 39 (clockwise, Fig. 2), against the action of the spring 50. This movement of the ratchet 40, (clockwise, Fig. 2), acts, through the link 43 to pivot the link mechanism 43—20—23 (from dotted to full line position, Fig. 2), thereby rotating the disc 27 and its arm 26 (clockwise, from dotted to full line position, Fig. 2) and thus closing the switch 38 and the circuit 61.

During the foregoing movement of the ratchet 40 (clockwise, Fig. 2) the teeth 41 of the ratchet 40 ride out of engagement with the arm 54 of the latch dog 53, whereupon the tensioned spring 56 acts upon the pawl 53 to pivot the same out of engagement with the teeth 41 of the ratchet 40, (clockwise, from the position in which it is shown in Fig. 2 into the position in which it is shown in Fig. 1), and during this operation the tensioned resetting spring 50 acts upon the ratchet 40 to pivot the latter, at 39, (counterclockwise, into the position in which it is shown in Fig. 1). During this movement of the ratchet 40 the angled arm 46 thereof engages under the bottom edge of the pawl 45—47 and thereby lifts the pawl 45—47 into its initial position, as in Fig. 1.

However, when the coin slide 14 and the slide bar 17 are returned to their initial position (as in Fig. 1) by the action of the resetting spring 58, the pin 57 will again engage the contact 58 and close the full stroke switch 60, and during the operation of the link mechanism 43—20—23 through the arm 26, and the disc 27 which will rotate (clockwise, Fig. 2), the latch pin 32 will again ride the periphery of the disc 27. During this operation the member 33 will again be pivoted, at 34, (Fig. 2), and this movement of the member 33 will cause the disc 35 carried thereby to engage the contact 36, thus urging the contact 36 into engagement with the contact 37 and thereby closing the switch 38, thus again closing the circuit 61 and rendering the operating mechanism (which, in the present instance is shown, for the purpose of illustration, as being the motor 63) effective.

After the operating mechanism (the motor 63, and associated parts) has been operated a predetermined length of time, the timing device 28 will again become effective to open the circuit 61 and thus prevent further operation of the operating mechanism 63, etc., this being accomplished by the movement of the disc 27 (counterclockwise, from full to dotted line position, Fig. 2). This movement of the disc 27 and its arm 26 also acts to reset the link mechanism 23—20—43 back into its initial position (as in dotted lines, Fig. 2, full lines, Fig. 1).

It will thus be seen that the ratchet 40 and associated parts provides a form of repeat mechanism which permits the operator of the device to effect two successive operations of the coin slide 14 and control device or operating mechanism 28 and associated parts, including the switch 38 and motor 63, for each coin inserted into the coin aperture of the coin slide 14, by taking advantage of the lost motion in the slide 14.

While we have illustrated and described the preferred form of construction for carrying our invention into effect, this is capable of variation and modification, without departing from the

spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. Coin controlled apparatus having a coin slide provided with detent means released to permit full stroke movement of the slide upon deposit of a coin therein, said slide having a normal limited idle stroke movement, a controlled instrumentality, link means connecting said instrumentality with said coin slide for operation of the former by the slide in full stroke movement of the latter, together with repeat operating mechanism operably connected with said link means and including an actuating member movable by operation of said link means, responsive to a movement of the latter by a slide in a full stroke movement of the slide, into a position for operative engagement with said link means for movement by the latter to operate said instrumentality when said slide is subsequently moved in idle stroke movement, and means cooperable with said repeat operating mechanism for automatically moving said actuating member out of position for further operative engagement with said link means until said slide is again moved in full stroke operation as aforesaid.

2. Control mechanism including a reciprocable control member and coin released detent means normally permitting limited idle stroke movement thereof and releasable to permit full stroke movement thereof, a controlled instrumentality, link means operatively connecting said control member with said instrumentality and constructed to operate when moved by said control member upon full stroke operation of the same, and means for operating said instrumentality once by moving said control member in an idle stroke movement of the same after a previous full stroke operation of the same, said means comprising a repeat operating mechanism for said instrumentality and provided with an actuating member having an operative connection with said link means and said control member and means operable by the control member upon full stroke operation of the latter to move said actuating member into effective position for subsequent movement by said link means independently of the aforesaid operative connection when the link means is moved by the control member upon idle stroke movement of the latter whereby to effect actuation of the instrumentality, and means for automatically moving said actuating member out of said effective position after said instrumentality has been operated by said repeat operating mechanism as aforesaid.

3. Control mechanism including a reciprocable control member and coin controlled means normally latching said member for limited reciprocable idle stroke movement, said means being releasable by a coin to permit said control to move through a full stroke, a controlled instrumentality and link means operatively connecting the same with said control for operation by full stroke movement of the latter, repeat operating mechanism and means operatively connecting the same with said link means for operating said instrumentality, said repeat operating mechanism having an actuating member movable into and out of position for engagement with and operation by said link means such that move-

- ment of the link means by said control member during an idle stroke movement thereof will actuate said instrumentality after a previous full stroke operation of the control member, together with releasable positioning and holding means automatically operable by full stroke movement of said control member to move and hold said actuating member in position for operation by said link means, spring means holding said releasable means in a normal position with the actuating member out of position for operation by said link means, said releasable means being automatically released from holding operation as soon as said actuating member has been moved to actuate said instrumentality.
4. Control mechanism including a reciprocable control member of the type having coin released means normally latching said member for limited reciprocable idle stroke movement, said means being releasable by a coin to permit said control to move through a full stroke, a controlled instrumentality and link means operatively connecting the same with said control for operation by full stroke movement of the latter, repeat operating mechanism and means operatively connecting the same with said link means, said repeat operating mechanism having an actuating member movable into and out of position for engagement and operation by means moved by said link means so that an idle stroke movement of the latter by said control during an idle stroke movement thereof will actuate said instrumentality after each previous full stroke operation of the control member, releasable positioning and holding means automatically operable by full stroke movement of said control member to move and hold said actuating member in position for operation by said link means, spring means holding said releasable means in a normal position with the actuating member out of position for operation by subsequent operation of said link means, said releasable means being automatically released from holding operation as soon as said actuating member has been moved to actuate said instrumentality.
5. A control device including a reciprocable coin slide having coin-free mechanism normally latching said slide against full stroke movement but permitting limited idle stroke movement of the slide, a controlled instrumentality, link means operatively linking said slide with said instrumentality for operation of the latter by the former in full stroke movement, together with repeat operating mechanism for said instrumentality and means operatively connecting the same with said link means and including a pivoted member movable to effect operation of said instrumentality, and pawl means movable thereby for operatively and temporarily associating said pivoted member with said first-mentioned link means for actuation of the pivoted member responsive to an idle stroke movement of said slide after the latter has been previously reciprocated through a full stroke as aforesaid, means normally positioning said pivoted member and said pawl means out of operative relationship with said link means, holding means automatically operable to hold said pivoted member and said pawl means thereof in position for operative engagement with said link means, said holding means being automatically released after said pivoted member is moved to operate said instrumentality.
6. Control means including a reciprocably movable coin slide and coin-free means releas-

ably latching the slide for limited idle stroke movement, said slide being operable through full stroke when a coin is deposited in said means, a controlled instrumentality, means including a pusher bar operably associated with said slide for reciprocation thereby and operatively connected with said instrumentality for actuation of the latter by full stroke movement of said slide, together with means for operating said instrumentality by said slide when the same is operated in idle stroke movement after first having been moved through full stroke, said last-mentioned means including a repeat operating mechanism for said instrumentality and having a pivoted member and link means operatively linking the same with said pusher bar and said instrumentality to actuate the instrumentality cooperably with said pusher bar, said repeat mechanism further having a pawl mounted on said pivoted member and movable by the latter into and out of position to be operatively associated with said pusher bar, said pusher bar being operable by said slide when the latter is operated in full stroke movement to move said pivoted member through the agency of said link means and position said pawl for operative association with the pusher bar whereby the latter may operate said repeat mechanism and said instrumentality when the slide is subsequently operated in an idle stroke movement, together with automatic means cooperable with said pivoted member to move said pawl out of position for operative engagement with said pusher bar each time the latter operates said instrumentality responsive to idle stroke movement of the slide.

7. Control means including a reciprocably movable control member provided with coin control mechanism normally permitting limited idle stroke movement of the control member and operable by a coin to free said control member for a full stroke operation, a controlled instrumentality, a pusher bar arranged to be reciprocated by said control member, link means operatively connecting said pusher bar and instrumentality and arranged to actuate the latter by a complete stroke of said control member, and means for operating said instrumentality by a partial stroke of the control member and said pusher bar, said means including an operating arm connected with said link means and with a pivoted member which is pivotable to move said operating arm and actuate said instrumentality through the agency of said link means, a pawl on said pivoted member and movable by the latter into a position for operative association with said pusher bar so that the pusher bar will move the pivoted member to actuate said instrumentality, spring means holding said pivoted member in a normal position with the pawl out of operative association with the pusher bar as aforesaid, said pusher bar being effective when moved in full stroke operation to move said pivoted member and position said pawl in cooperative relation to the pusher bar for the purpose aforesaid, together with automatic latching mechanism operable to hold said pivoted member with said pawl in operative position as aforesaid for cooperation with the pusher bar until said pusher bar and said pawl have been moved by an idle stroke movement of said control to actuate said instrumentality, whereupon said spring means will restore the pivoted member and pawl to normal position.
